(57) **CLAIM**

The ornamental design for an elastic bandage with anchoring part, as shown and described.

DESCRIPTION

FIG. 1 is a right top perspective view of an elastic bandage with anchoring part, according to our new design;

FIG. 2 is a right side view thereof;

FIG. 3 is left side perspective view thereof; and,

FIG. 4 is a bottom perspective view thereof.

In the drawings, the dashed broken lines depict portions of the elastic bandage with anchoring part that form no part of the claimed design. The dot-dash lines represent a symbolic break in its length. The appearance of any portion of the article beyond the break forms no part of the claimed design.
